Duell, Warner & Co.
ATTORNEY

UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO

MANIFOLDING SALES BOOK

Application filed May 28, 1922. Serial No. 562,958.

This invention relates to manifolding devices and with respect to its more specific features to manifolding books, pads and the like and elements thereof.

5 One of the objects of the invention is the provision of a practical manifolding unit adapted for making four, or five records at one writing and capable of simple manipulation for setting in manifolding relation and 10 for removing from manifolding relation.

Another object of the invention is the provision of a device of the character referred to adapted for making a large number of records at one writing and requiring a minimum 15 of separate transfer leaves.

Other objects will be in part obvious and in part pointed out hereinafter.

The invention accordingly consists in the features of construction, combinations of elements and arrangements of parts which will 20 be exemplified in the construction hereinafter set forth, and the scope of the application of which will be indicated in the following claims.

25 In the accompanying drawing forming part of the specification and wherein similar reference characters refer to similar parts throughout the several views.

Figure 1 is a perspective view of a mani- 30 folding pad embodying the invention; and Fig. 2 is a side view of a modified form.

Referring now more specifically to the drawings and particularly to Fig. 1 thereof, the numeral 1 indicates a pad of record leaves, the leaves being made of paper such that when the leaves are superposed one upon another with the interposition of transfer material a writing made upon an upper leaf will be transferred to underlying leaves. In 35 the embodiment now referred to the paper is relatively opaque and four opaque direct copies are made at one writing. It will be understood, however, that translucent material, as tissue paper, may be employed. The 40

45 pad 1 is composed of a plurality of superposed record sheets bound together at one end by the staples 2. As all of these sheets are alike the description of one will suffice.

One of these sheets is shown in open condition in Fig. 1 and is composed of the four

leaves 3, 4, 5 and 6, the leaves 3, 5 and 6 being of substantially the same length and width, the leaf 4 having an extended or stub portion 7 for binding purposes, and weakened along the line 8 in order that it may be 55 readily torn from the stub portion.

Each of the record sheets is formed from a strip which is first folded along the line 9, to provide a folded record sheet of two plies. Thereupon this two ply folded sheet is again 60 folded intermediate its ends on lines parallel with the line 9 as generally indicated at 10, so as to provide the four relatively superposed integrally connected record leaves 3, 4, 5 and 6 above referred to. 65

One or more of the record leaves are coated with transfer material, as carbon, upon their underfaces in order to transfer inscription from adjacent superposed leaves. In 70 Fig. 1 the original record leaf 3 and the duplicate record leaf 5 are thus coated, as illustrated. In the present embodiment the triplicate leaf 6 and the quadruplicate leaf 4 are not coated with transfer material.

Each of the record sheets above referred to is also provided with a transparent, as tissue, record leaf pasted thereto. In the embodiment illustrated in Fig. 1 the transparent tissue record leaf is indicated at 11 and is pasted to the upper face of the quadruplicate leaf 4 at or adjacent the fold line 10 between the leaves 3 and 4. The pasted area is indicated by the shading at 12 and the margin of the pasted area may substantially correspond with the fold line 10 at this position. The numeral 13 indicates a separate transfer leaf which is adapted to lie on the upper face of the record leaf 4 and against the under face of the supplemental tissue leaf 11, so as to transfer inscription direct to the leaf 4 and in reverse to the leaf 11. The separate transfer leaf 13 may be bound in with the record sheets by means of the staple 2 and is coated with carbon on both faces. 85

If desired, the supplemental transfer leaves 11 of the several sets may be omitted whereupon four records may be made at one writing as illustrated in Fig. 2. 90

Fig. 1 diagrammatically illustrates the 100 relative positions of the various record leaves

and transfer material when the book is set for the manifolding operation, it being understood of course that in the actual book the sheets are flattened out so as to be serviceable for inscription. A record impressed upon the topmost leaf 3 will be transferred to the next underlying record leaf 5 by the carbon coating on the underface of the topmost leaf. Also the transfer material on the underface of the record leaf 5 will transfer impression direct to the triplicate leaf 6. The same impression will be transferred direct to the lowermost leaf 4 of the set by the separate transfer leaf 13, and in reverse to the underface of the tissue leaf 11.

15 After inscription the inscribed set of leaves may be manipulated and detached from the stub along the weakened line 8 by grasping them at the fold line between the leaves 3 and 4. After removal the transfer leaf 13 will be found lying upon the next uppermost set. Thereupon the leaves 3, 5, 6 and 11 of the next set may be readily lifted by passing the finger under those ends adjacent the stub, 20 whereupon the transfer leaf 13 may be inserted in operative manifolding position.

Thus by the above described construction are accomplished among others the objects hereinbefore referred to.

25 30 As many changes could be made in the above construction and many apparently widely different embodiments of this invention could be made without departing from the scope thereof, it is intended that all matter contained in the above description or 35 shown in the accompanying drawing shall be interpreted as illustrative and not in a limiting sense.

Having described my invention, what I 40 claim as new and desire to secure by Letters Patent is:

1. A manifolding pad comprising in combination a set of leaves including four leaves attached together end to end to form a strip, 45 said strip being folded to superpose the third and fourth leaves upon the second and first respectively, and being folded a second time to bring the four leaves of the set in registry with each other, the first leaf of said set 50 being extended from the others to form an extension by which the set may be attached with other similar sets in the pad, and an auxiliary leaf attached to said first leaf near the fold and extending toward said extension on said first sheet, a carbon sheet bound within the pad adapted to lie between the first and fourth sheets, and carbonized underfaces upon the second and third sheets.

55 2. A manifolding pad comprising, in combination, a set of leaves including four leaves attached together end to end to form a strip, said strip being folded to superpose the third and fourth leaves upon the second and first respectively, and being folded a second 60 time to bring the four leaves of the set in

registry with each other, the first leaf of said set being extended from the others to form an extension by which the set may be attached with other similar sets in the pad, and an auxiliary leaf attached to said first leaf near the fold and extending toward said extension on said first sheet, a carbon sheet bound within the pad adapted to lie between the first and fourth sheets, and transfer material for transferring inscriptions to said 70 third and fourth sheets.

75 In testimony whereof I affix my signature.

EDWARD KIRBY BOTTLE.
